(57) **CLAIM**

The ornamental design for portion of a display screen with a graphical user interface, as shown and described.

DESCRIPTION

FIG. 1 is a front view of a portion of a display screen with a graphical user interface showing the new design; FIG. 2 is a front view of a second embodiment thereof; and, FIG. 3 is a front view of a third embodiment thereof. The dashed lines showing text and images form no part of the claimed design. Said dashed lines, dashed image, and text are presented only for environmental purposes.
